UNITED STATES PATENT OFFICE.

CALVIN C. YATES, OF LEE, MASSACHUSETTS.

STUFF-BOX REGULATOR.

Application filed January 11, 1922. Serial No. 528,513.

To all whom it may concern:

Be it known that I, CALVIN C. YATES, a citizen of the United States, residing at Lee, county of Berkshire, and State of Massachusetts, have invented certain new and useful Improvements in Stuff-Box Regulators, fully described and represented in the following specification and the accompanying drawings, forming a part of the same.

10 This invention relates to improvements in stock regulating devices for paper making machines.

In making paper the stock, which is in the form of pulp mixed with water, is fed to the paper making machine, as for instance, to the making wire of a Fourdrinier machine through an adjustable gate from a box technically known as the stuff box. The stock is supplied to this stuff box from a stuff 20 chest by a pump. To ensure there always being sufficient stock, the stock is supplied by the pump in quantities greater than flows to the wire, and the box is therefore provided with an overflow for carrying off the 25 surplus, this overflow returning the surplus back to the stuff chest from which the stock is pumped. This stock varies as to its consistency, that is, the pulp or fibre content of the stock will vary so that at times 30 thick stock is delivered by the pump and at other times thin stock, that is stock in which less pulp is present. The gate through which the stock is delivered to the wire of the paper making machine is adjusted for a given weight of paper, that is 35 the gate is adjusted so as to permit sufficient stock to pass through over the wire to make a paper of a certain weight. If the stock were delivered with the varying pulp 40 content as supplied to the stuff chest irregularities in the paper occur.

When thick stock is supplied to the stuff box it does not flow away so freely from the overflow and consequently the stock 45 piles up in the box and too much stock is delivered. On the other hand, thin stock flows away too freely and not sufficient stock is delivered at the gate to form a sheet of the required weight.

50 It is the especial object of the present invention to provide a regulator by which these variations in the consistency of the stock supplied to the box may be automatically equalized, the gate adjustment having 55 been once set for a given run remaining fixed so that this adjustment does not have

to be changed and an even equal run of stock through the gate may be obtained. This object is effected by so delivering the stock that the head or pressure of the stock 60 is varied as the stock increases or decreases in thickness, so that when the stock is thick the stock is delivered under less pressure and thereby in less volume per unit of time, and when the stock is thin the pressure is increased 65 so as to deliver the stock in greater volume per time unit, and thus equalize the pulp content of the stock at the wire, so that having a given gate adjustment the pulp content of the stock delivered is the 70 same whether the stock be thick or thin.

It is a further object of the present invention to effect the control of the stock by the head or pressure of the stock in the stuff box, and to provide a simple and efficient 75 apparatus for effecting these objects.

With these and other objects not specifically referred to in view, the invention consists in certain novel parts, combinations and arrangements, which will be fully described in connection with the accompanying drawings, and the novel features of which will then be pointed out in the claims hereunto annexed.

In these drawings—

85 Figure 1 is a plan view of one form of apparatus for effecting the automatic regulation of the stock.

Figure 2 is a section through the regulator proper, the section being taken on line 90 2—2 of Figs. 1 and 3.

Figure 3 is a side view, partly in section, looking in the direction of arrow 3 of Fig. 2.

Figure 4 is a detail view on an enlarged scale of the float arm and its connection to 95 the regulator.

Figure 5 is a detail sectional view, the section being taken on line 5—5 of Fig. 4.

Figure 6 is an end view; and

Figure 7 is a side view of a modified form 100 of apparatus.

Referring to these drawings and first to Figs. 1 to 5, there is shown a stuff box marked 1, supported on frames 2 rising from a suitable base 3, this stuff box being located 105 in a convenient point adjacent the paper making machine, not shown. Stuff is supplied to this box, preferably from another box 4, from a suitable source of supply by a pump, not illustrated, through a pipe 4', 110 this pipe leading into the bottom of the box, this construction being adapted to ensure

a steady flow of stock, not affected by the pulsations of the pump.

In carrying out the invention the usual practice of providing a gate somewhere in the walls of this box from which stock is delivered to the wire is departed from and there is provided a regulator separate from the box to which the stock is delivered from the box. This regulator is in the form of a movable chamber, and it is provided with a delivery opening, which may be an adjustable gate through which the stock is delivered, such construction being illustrated in Figs. 1 to 5. While the particular form of this chamber may be varied, the chamber will be arranged and constructed so that it may be movable in order that the delivery opening may be moved up or down so as to increase or decrease the head or pressure of the stock in the chamber, so that such stock will be delivered from the gate under a greater or less head or pressure, depending on the thickness of the stock, and the movement of this chamber will be controlled by the head or pressure of the stock in the stuff box, this head or pressure of the stock in the stuff box varying according to the pulp content.

In the particular construction illustrated there is provided a movable chamber 5 located closely adjacent the stuff box 1 and to which stuff is delivered from the stuff box through a sluice 6 formed in the upper part of one of the walls of the box. This chamber is in the form of a circular drum or cylinder having closed ends and which is provided with a top opening 7 into which stock flows from the sluice 6. This drum has formed in its upper part an overflow outlet, indicated at 8, which delivers into a sluice 9, and from this sluice surplus stock may be returned to the source of supply by a pipe 10. The drum is also provided with a delivery outlet 11 formed in the drum walls below the discharge outlet 8, just referred to, this outlet leading to a sluice 12 carried by the drum walls, this sluice delivering to the flow box 13 from which the stock is delivered to the wire of the machine not shown.

The delivery outlet 11 in the construction shown in Figs. 1 to 5 is controlled by a gate 14 mounted to slide in guides 15 in the drum walls. This gate is adjustable in the guides and is set for any given run of the machine, and having once been adjusted remains the same for such run. The gate may be adjustable in various ways, but in the particular construction illustrated there is shown a screw rod 16 working through a thrust block 17 carried in a bracket 18 fast to the drum, the rod being manipulated by means of a hand wheel 19 to effect the adjustment of the gate.

In accordance with the invention, mecha-

nism is provided for rotating this drum to vary the pressure head of the stock therein. As for instance, by turning the drum to the left in the direction of the arrow in Fig. 2, the outlet would be raised and consequently the pressure head would be decreased, and vice versa, and in constructions embodying the invention the movement in this drum is controlled by the head or pressure of the stock in the stuff box. While various means may be provided for effecting this, in the particular construction illustrated, there is provided a float 20 in the stuff box 1, before referred to. This float has connected thereto a pair of arms 21 pivoted on a rock shaft 22 supported in brackets 23 secured to the sides of the stuff chest. On this rock shaft is an arm 24, the other end of this arm being connected with the end of the drum. In the best constructions this connection is adjustable so that the end of the arm can be moved toward and from the center of the drum for adjusting the throw that is given to the drum by the movement of the arm. While this may be effected in various ways, in the particular construction illustrated, there is provided a plate 25 formed with a slot 26 in which may be positioned a bolt 27, this bolt being held in position in the slot 26 by means of a nut 28. This bolt at its outer ends extends through a slot 29 formed in the end of the arm 24, the bolt having a nut 30 for holding the arm in position, the arm working on the shank of this bolt as it is moved by the float. With this construction the arc of the swinging movement of the arm may be lengthened or diminished, and this acts to vary the movement of the drum as desired.

Referring now to Figs. 6 and 7, in the construction shown in these figures the adjustable gate 14, before referred to, is omitted, and the regulator chamber is made to effect the functions of the gate. Means are provided for adjusting the regulator so that for a given run to make a given weight of paper the regulator chamber may be moved to the right or left thus raising or lowering the delivery outlet 11, so that under normal conditions the stock will flow through under a certain head or pressure and in the required volume. If, however, the conditions become abnormal, the regulator is operated, as before described, to vary the pressure at the delivery and consequently the volume per unit of time, this operation being controlled by the pressure head in the stuff box as before described.

In the particular apparatus illustrated the chamber is provided with an adjusting device by which it can be rotated independently of the float, for adjusting it for a particular run. As shown the lever arm 24 instead of extending downward on the side of the

drum extends straight across above the drum and is provided with a slot 40 in which takes the upper end of a screw rod 41 on which is a hand wheel 42 by which the rod may be moved up, the usual thrust collars 43 being provided on the rod on each side of the arm 24. The other end of the rod 41 has secured thereto a pin 44 which takes in a slotted plate 45 fast on one end of the drum, this 10 pin being adjustably held in the slot by a lock nut 46. With this construction the rod may be moved toward or from the periphery of the drum, and thus the movement imparted by the float arm 24 to the 15 drum may be varied as desired.

With this modified construction the regulations of the stock is effected as before described. The stock when thick causes an upward movement of the float which causes the 20 drum to be rotated so that the delivery opening is raised, thus lowering the overflow outlet and reducing the pressure at which the stock is fed. Vice versa when the float drops the delivery opening is moved downwardly 25 thus increasing the pressure and the volume of stock delivered per unit of time.

With the construction described the stock is delivered from the stuff box to the regulator drum. As the pulp content or stock 30 increases in thickness the stock piles up in the stuff box, lifts the float, which in turn rotates the drum to the left, as shown in Fig. 2, so that the gate is elevated and the pressure head reduced thereby slowing down the 35 delivery of stock per time unit through the gate. When the stock is thin, however, the reverse movement takes place, the stock flowing freely away from the stuff box permitting the float to drop which rotates the drum 40 so as to lower the delivery opening and thus increase the pressure head supplying stock in greater volume per time unit.

While the invention has been shown in what is thought to be its best form, it will 45 be understood that changes and variations may be made in the specific mechanism by which the pressure head is regulated, and that the invention is not to be restricted to the exact mechanism described in the specification and illustrated in the drawings.

What I claim is:

1. In an apparatus of the class described, the combination with a stuff box and means 55 for delivering stock thereto, a regulator chamber to which the stock is delivered from the box, a delivery opening in the chamber, and means controlled by the consistency of the stock in the box for increasing or decreasing the pressure head of the stock in the chamber to vary the volume of stock passing through the delivery opening per unit of time.

2. In an apparatus of the class described, the combination with a stuff box and means 60 for delivering stock thereto, a movable regu-

lator chamber having a delivery opening and an outlet, and means for moving the chamber for raising or lowering the delivery outlet to increase or decrease the pressure head of the stock in the chamber. 70

3. In an apparatus of the class described, the combination with a stuff box and means for delivering stock thereto, a rotary regulator chamber having a delivery opening and an outlet, and means for rotating the 75 chamber to raise and lower the delivery outlet to increase or decrease the pressure head of the stock in the chamber.

4. In a stuff regulator for paper making machines, the combination of a stuff box and 80 means for supplying stock thereto, a float in the box, a movable regulator chamber to which stock is delivered from the box, a delivery opening in the chamber, and connections between the float and the chamber for 85 moving the chamber to increase or decrease the pressure head of the stock in the chamber.

5. In a stuff regulator for paper making machines, the combination of a stuff box and 90 means for supplying stock thereto, a float in the box, a rotary regulator chamber to which stock is delivered from the box, a delivery opening in the chamber, and connections between the float and the chamber for 95 rotating the chamber to increase or decrease the pressure head of the stock in the chamber.

6. In a stuff regulator for paper making machines, the combination of a stuff box and 100 means for supplying stock thereto, a float in the chamber, a movable regulator chamber to which stock is delivered from the box, a delivery opening in the chamber, means for varying the volume of stock passing through 105 the delivery opening for a given run, and connections between the float and the chamber for moving the chamber to increase or decrease the pressure head of the stock in the chamber.

7. In a stuff regulator for paper making 110 machines, the combination of a stuff box and means for supplying stock thereto, a float in the box, a movable chamber to which stock is delivered from the box operated from the float to vary the pressure head of the stock 115 in the chamber, and means for varying the movement given the chamber by the float.

8. In a stuff regulator for paper making machines, the combination of a stuff box and 120 means for supplying stock thereto, a float in the box, a movable chamber to which the stock is delivered and having a delivery outlet and moved by the float, means for varying the volume of stock passing the delivery opening for a given run, and means for varying the movement given the chamber by the float.

9. In a stuff regulator, a stuff box, a movable chamber to which stock is delivered 130 from the box, a float in the box, and a float

arm connected to the chamber for moving it.

10. In a stuff regulator, a stuff box, a rotary chamber to which stock is delivered from the box, a float in the box, and a float arm connected to the chamber for rotating it.

11. In a stuff regulator, a stuff box, a rotary chamber to which stock is delivered from the box, a float in the box, a float arm connected to the chamber, and means for moving the point of connection toward and from the periphery of the chamber.

12. In a stuff regulator, a stuff box, a movable chamber to which stock is delivered from the box, a delivery gate carried by the chamber, means for adjusting the gate, a float in the box, and connections between the float and chamber for moving it.

13. In a stuff regulator, a stuff box, a rotary chamber to which stock is delivered from the box, a delivery gate carried by the chamber, means for adjusting the gate, a float in the box, connections between the float and chamber for moving it, and means

for varying the amount of movement given the chamber by the float.

14. In a stuff regulator, a stuff box, a movable chamber to which stock is delivered from the box and having a delivery opening, means for adjusting the amount of stock passing through the opening for normal running, a float in the box, a float arm, connections from the arm to the chamber, and means for adjusting the connections to vary the movement given the chamber by the arm.

15. In a stuff box regulator, the combination with the stuff box and means for delivering stock thereto, of a regulator chamber to which stock is delivered from the box and from which stock is delivered, and means controlled by pressure in the box for manipulating the chamber to vary the volume of stock per unit of time delivered therefrom.

In testimony whereof, I have hereunto set my hand.

CALVIN C. YATES.
